UNITED STATES PATENT OFFICE.

ALBERT LIEBER AND JOHN J. GAYNOR, OF INDIANAPOLIS, INDIANA, ASSIGNEES TO
THE L. & G. MANUFACTURING CO., OF INDIANAPOLIS, INDIANA, A CORPORATION.

BOTTLE-LABELING MACHINE.

1,179,442.

Specification of Letters Patent. Patented Apr. 18, 1916.

Application filed July 8, 1915. Serial No. 38,697.

To all whom it may concern:

Be it known that we, ALBERT LIEBER and JOHN J. GAYNOR, citizens of the United States, residing at Indianapolis, in the county of Marion and State of Indiana, have invented certain new and useful Improvements in Bottle-Labeling Machines; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to bottle labeling machines and has for its object to provide an automatic bottle labeling device, so constructed and arranged that the bottles are conveyed successively to the labeling mechanism to receive one or more labels, after which the said bottles are delivered from the machine.

A further object of the invention is to provide certain improvements over the application of John J. Gaynor for Letters Patent of the United States for bottle labeling machines, Serial No. 24982, filed April 30, 1915, said improvements over said application consisting in the construction and arrangement of the label boxes, the construction and arrangement of the cam for actuating the label carriers and in the construction and arrangement for holding the label carriers in their proper normal position.

With these and other objects in view the invention consists in the novel construction and arrangement of the label boxes.

The invention further consists in the novel construction and arrangement of label carriers, their cam for actuating the same and their self-contained means for holding the same in their proper normal position.

The invention further consists in certain novel details of construction and in certain combinations of parts, all of which will be first fully described and afterward specifically pointed out in the appended claims.

Referring to the accompanying drawings—Figure 1 is an elevation of a bottle labeling machine constructed in accordance with this invention. Fig. 2 is a fragmentary side elevation of the same illustrating the label

carriers and label boxes. Fig. 3 is an enlarged transverse vertical sectional view through one of the shafts and bearings of one of the label carriers taken on line 3—3 of Fig. 2, and Fig. 4 is a similar view illustrating these parts in unlocked position as when under the influence of the actuating cam.

Like numerals of reference indicate the same parts throughout the several figures, in which—

1 indicates the bottle labeling machine which comprises a suitable frame-work 2 having the longitudinal frame-pieces 3, 4 and 5.

6 indicates a shaft journaled in the upper frame-piece 3, by means of which shaft the machine is driven. Mounted also on said shaft 6 is a sprocket wheel 7 chained to a sprocket 8 which is mounted on a shaft 9 of a paste roller 10 in the paste box 11, a distributing paste roller 12 being mounted in contact with the paste-roller 10 to receive paste therefrom.

13 indicates the stationary cam which as shown is provided with the groove 14 in which the rollers 15 of the label carrier 16 operate, said label carrier 16 comprising a shaft 17 mounted in a bearing 18 on the spider 19. A crank 20 secured to said shaft 17 carries the roller 15 so that when the said roller 15 is moved or actuated by the slot 14 of the cam 13, the bifurcated label carrier 21 is moved into the several positions shown in Fig. 1, it being understood that the spider 19 carrying the four label carriers 16 is rotated by the shaft 6, so that each of the label carriers 16 successively assumes the position shown in Fig. 1.

22 indicates the vertical rotating table 95 which is in reality a large spur gear driven from the shaft 6 in any convenient manner and journaled in the transverse frame-piece 4. Said vertical rotating table 22 carries the carriers 23 and the label engaging fingers 24, said bottle carriers 23 being pivoted at 25 and are each provided with a roller 26, which is arranged in the path of the stationary rail 27, suitable means being provided as by springs (not shown) for swinging bottle carriers 23 into their normal positions after their rollers 26 have passed out of engagement with the rail 27.

28 indicates the bottle conveyer chain which passes over a sprocket 29 at the re-

ceiving side of the machine and which passes downwardly and over a sprocket 30 at the delivery end of the machine, it being understood that the said conveyer 28 delivers bottles to the machine and receives bottles therefrom.

Referring now to the label boxes 31 it will be seen that the same are mounted on a shaft 32 on the end of which is a spur gear wheel 33 meshing with a spur gear wheel 34 on the shaft 6, the ratio of the said gears being two to one, so that upon every revolution of the shaft 6 and the label carriers 16 the gear, shaft 32 and label boxes 31 make two complete revolutions. As there are two label boxes 31 and four label carriers 16 the parts are arranged so that a rolling contact will be effected between the bifurcated label carriers 21 and the label in the boxes 31 in the manner as is illustrated in Fig. 1.

As will appear from the drawings the label boxes 31 include label holding arms 35, a follower 36 guided thereby and a notched follower stem 37, said stem being in engagement with a small leaf spring 38 so that the follower 36 will be maintained in close contact with the labels in the box, and so that they will always exert sufficient pressure upon the labels to insure a proper and continuous feed of labels therefrom.

As it is sometimes desired to simultaneously apply two labels to a bottle, we have shown in Fig. 2 two sets of label boxes, so that two labels can simultaneously be picked up and carried by each of the bifurcated label carriers 21.

Referring now particularly to Figs. 3 and 4 it will be seen that we provide the shaft 17 of each of the label carriers 16 with a tapered cavity 39, and upon the bearing 18 for each of the shafts 17 we apply a cap 40 inclosing a coil spring 41 which spring 41 bears against a headed plunger 42 having a tapered point 43, so that when the shaft 17 is swung by the cam 13 to cause the tapered cavity 39 to register with the plunger 42, said plunger 42 will enter the cavity 39 in the shaft 17 to lock said shaft in its proper normal position, as when the bifurcated label carrier 21 is receiving a label from one of the label boxes. As soon however, as the roller 15 of the label carrier 16 is influenced by the cam 13 the label carrier shaft 17 is swung out of position shown in Fig. 3 and into position shown in Fig. 4, or in any intermediate position, according to the formation of the cam 13, said cam however, is so shaped that before the roller 15 passes therefrom the same is caused to assume a position which brings the label carrier shaft 17 into position shown in Fig. 3 to lock said shaft to its bearing 18, so that the bifurcated label carrier 21 properly receives its label or labels from the label boxes,

Having thus described the several parts of this invention, its operation is as follows: The bottles conveyed to the machine by the conveyer 28 are received by one of the bottle carriers 23, said bottle carrier being in position shown in Fig. 1 to receive a bottle from the said conveyer. Said bottle carrier 23 is maintained in like position until its roller 26 passes out of engagement with the rail 27. By means of a spring (not shown) the bottle carrier 23 is swung inwardly of the rotating table 22 which carries its bottle into engagement with the label affixing finger 24. While the said bottle carrier roller 26 is yet in engagement with the rail 27 the bifurcated label carrying finger 21 deposits its label on the label affixing finger 24, so that when the bottle carrier 23 is swung inwardly the bottle therein is caused to engage the label deposited on the label affixing finger 24 by the bifurcated label carrier 21, in the manner as has been heretofore fully described in said application for Letters Patent before referred to, and which construction forms no part of the invention to which this present application is directed. As each of the bifurcated label carriers 21 deposits a label on the label applying and affixing finger 24, the same continue their rotation and come in rolling contact with the paste distributing roll 12, and thence pass to the label boxes 31 to receive a label or labels therefrom. As the label carriers continue to rotate they become influenced by the cam 13 and are swung out of their normal position for the purpose of meeting and depositing their label or labels on the label applying fingers 24. After the label or labels have been applied to a bottle the same pass through the label wipers 44 which wipe and smooth out the label or labels on the bottles, after which the roller 26 on each of the bottle carriers 23 engages the rail 27 which rail swings the bottle carrier 23 outwardly of the vertical rotating table 22, thus carrying the bottle out of engagement with its label affixing finger 24, and delivering the bottle upon the conveyer 28 in a labeled condition.

Having thus fully described the invention it is apparent that the same is susceptible to certain changes and alterations in the construction and arrangement of the parts, and we consider ourselves clearly entitled to all such changes and modifications as fall within the limit and scope of the appended claims.

What we claim as new and desire to secure by Letters Patent of the United States is—

1. A bottle labeling machine, including a vertically disposed rotatable member, a plurality of bottle carriers pivoted thereon, means associated with said carriers to swing the same on their pivots, a conveyer having extensions thereon to form spaces or recesses,

- to receive bottles to convey the same to and from said bottle carriers, label receiving and conveying devices associated with said vertical rotatable member and with said bottle carriers, means for applying paste to said label receiving and carrying devices, a plurality of rotatable label boxes associated with said label receiving and conveying devices to deposit a plurality of labels thereon and to 5 convey the same to said bottle carriers to be applied thereby to the bottles, and means for wiping the labels so applied.
2. A bottle labeling machine, including a vertically disposed rotatable member, a plurality of bottle carriers movably mounted thereon, a conveyer having extensions thereon to form spaces or recesses to receive bottles to convey the same to and from said bottle carriers, means associated with said carriers to move the same on said rotatable member to receive bottles from and deliver bottles to said conveyer, label receiving and conveying devices associated with said vertical rotatable member and with said bottle carriers, means for applying paste to said label receiving and carrying devices, a plurality of rotatable label boxes associated with said label receiving and conveying devices to deposit a plurality of labels thereon, and to 10 convey the same to said bottle carriers to be applied thereby to the bottles.
3. A bottle labeling machine, including a vertically disposed rotatable member, a plurality of bottle carriers movably mounted thereon, a conveyer to receive bottles to convey the same to and from said bottle carriers, means for moving said carriers on said rotatable member to receive bottles from and deliver bottles to said conveyer, label receiving and conveying devices associated with said vertical rotatable member and with said bottle carriers, means for applying paste to said label receiving and carrying devices, a rotatable label box associated with said label receiving and conveying devices to deposit a label thereon to be conveyed to said bottle carriers to be applied by said label receiving and conveying devices to the bottles, and means for wiping the labels so applied.
4. A bottle labeling machine, including a vertically disposed rotatable member, a plurality of bottle carriers movably mounted thereon, a conveyer having means to receive bottles to convey the same to and from said bottle carriers, means for moving said carriers on said rotatable member to receive bottles from said conveyer, label receiving and conveying devices associated with said vertical rotatable member and with said bottle carriers, means for applying paste to said label receiving and carrying devices, a rotatable label box associated with said label receiving and conveying devices to deposit a 15 label thereon and to convey the same to said bottle carriers to apply same to the bottles.
5. A bottle labeling machine, including a plurality of rotary cam actuated label carriers, means for applying paste thereto, a plurality of rotary label boxes adapted to carry labels to effect a rolling contact between the said rotary label carriers and the said labels in the said rotary label boxes, and means for holding a bottle in position to receive a label from one of said label carriers.
6. A bottle labeling machine, including a plurality of rotary cam actuated label carriers, a spider mounting said carriers, a shaft for each of said carriers, each shaft being provided with an aperture, the said spider including a spring actuated plunger adapted to enter the aperture in each of said shafts to lock the same and the label carriers in their proper normal position, and means for holding a bottle in position to receive a label from one of said label carriers.
7. A bottle labeling machine, including a plurality of rotary cam actuated label carriers, a spider mounting the same, self-contained means for locking and holding the said label carriers in their proper normal position, and means for holding a bottle in position to receive a label from one of said label carriers.
8. A bottle labeling machine, including a plurality of rotary cam actuated label carriers, means for pivoting said rotary label carriers, said label carriers being adapted to swing on their pivots under cam influence, self-contained means for locking and holding said label carriers in their proper normal position, and means for holding a bottle in position to receive a label from one of said label carriers.
9. A bottle labeling machine, including a plurality of rotary cam actuated label carriers, a rotary label box associated with said rotary label carriers and adapted to hold a label for rolling contact with one of said rotary label carriers, and means for holding a bottle in position to receive a label from one of said label carriers.

In testimony whereof, we affix our signatures, in presence of two witnesses.
